UNITED STATES PATENT OFFICE.

MARK RICHARDS MUCKLE, JR., AND WILLIAM H. B. TEAMER, OF PHILADELPHIA, PENNSYLVANIA; SAID TEAMER ASSIGNOR TO SAID MUCKLE.

COVER FOR MAN-HOLE CHAMBERS OF UNDERGROUND CONDUITS.

SPECIFICATION forming part of Letters Patent No. 392,877, dated November 13, 1883.

Application filed June 11, 1883. Serial No. 276,677. (No model.)

To all whom it may concern:

Be it known that we, MARK RICHARDS MUCKLE, Jr., and WILLIAM H. B. TEAMER, both citizens of the United States, and residents 5 of Philadelphia, Pennsylvania, have invented certain Improvements in Covers for Man-Hole Chambers of Underground Conduits, of which the following is a specification.

One object of our invention is to so construct the cover for the man-hole chamber of an underground - conduit system that a portion of said cover can be readily thrown up whenever there is a heavy pressure within the man-hole chamber—such, for instance, as might 15 be caused by the explosion of gas which has leaked into the chamber; and a further object of our invention is to permit ready access to the interior of the man-hole chamber without the necessity of removing the entire cover. 20 These objects we attain in the manner herein-after set forth, reference being had to the accompanying drawings, in which—

Figure 1 is a longitudinal section of the upper part of the structure of a man-hole chamber with cover constructed in accordance with our invention; Fig. 2, a similar view showing another form of the cover; and Figs. 3 and 4, partial plan views of the structures shown, respectively, in Figs. 1 and 2.

30 A represents the cast-iron box or casing forming the upper part of the structure, which incloses the man-hole chamber, the upper portion of this box being recessed to receive the outer portion of the cover.

35 As shown in Fig. 1, the cover comprises two parts or sections, B B', the former being a fixed section and being secured to the casing A, so far as regards vertical movement, by the engagement of hooked lugs a on the under 40 side of the cover, with internally-projecting ribs b on the casing a.

The section B' of the cover is movable and is hinged to the fixed section B, preferably by means of links D, one end of each of which is 45 pivoted to the fixed section by means of a pin, d, and the other to the movable section by means of a pin, f, so that in the event of an explosion in the man-hole chamber, or of sudden or excessive pressure therein from any 50 other cause, the movable section of the cover will be free to swing up, so as to permit the

escape of gas or air in sufficient volume to relieve the pressure.

A check-chain, g, serves to so limit the rise of the movable section of the cover that the 55 same will again fall into place when the pressure is relieved; but this chain can be readily detached when it is desired to turn the movable section over onto the fixed section, as shown by dotted lines in Figs. 1 and 2, in order to gain access to the man-hole chamber without removing the entire cover. When it is desired to remove the entire cover from the man-hole chamber, however, the section B' is first lifted until its outer free end is above the 60 level on the casing A and the check-chain is detached, whereupon the entire cover may be moved longitudinally until the lugs a are free from engagement with the ribs b, and the vertical removal of the fixed section is permitted. 65 70

In Figs. 2 and 4 we have shown another form of our improved cover, in which both sections B B' of the same are movable, the fixed portion of the cover in this case being a central pivot-pin, d', which has at each end a 75 hooked lug, a, engaging with the internal ribs, b, on the casing A, each section of the cover being hung to this pivot-pin by means of a link-section, D', pivoted to the cover by a pin, f'. The casing A is preferably provided with internal lugs on all four sides, so that in whatever direction the cover may be applied to the casing proper means will always be afforded for the securing of the fixed portion of the cover to said casing. 80 85

When the throwing of one section of the cover over onto the other is not considered necessary, the sections may be hinged directly one to another without the interposition of the links; but the latter are preferred in all cases. 90

Having thus described our invention, what we claim, and desire to secure by Letters Patent, is—

1. The within-described cover for man-hole chambers of underground conduits, said cover 95 consisting of two or more sections bearing upon the man-hole casing at their outer edges and connected by a transverse hinge where they meet, all substantially as specified.

2. The within-described cover for man-hole chambers, said cover comprising a fixed portion, and a movable portion hung to said fixed 100

portion by means of one or more links, all substantially as specified.

3. The combination of the casing of a man-hole chamber with a cover having a section vertically confined to said casing and a movable section hinged to said fixed section, all substantially as specified.

4. The combination of the man-hole chamber casing having internally-projecting ribs with a cover comprising a fixed portion having lugs for engaging with said ribs, and a movable

portion hinged to said fixed portion, all substantially as specified.

In testimony whereof we have signed our names to this specification in the presence of 15 two subscribing witnesses.

M. RICHARDS MUCKLE, JR.
W. H. B. TEAMER.
